Inventor:
Henry Jensen
By J. M. Roberts, his Atty.

UNITED STATES PATENT OFFICE.

HENRY JENSEN, OF CHICAGO, ILLINOIS.

TOY.

1,410,188.

Specification of Letters Patent. Patented Mar. 21, 1922.

Application filed May 20, 1921. Serial No. 471,195.

To all whom it may concern:

Be it known that I, HENRY JENSEN, a citizen of the United States, residing at Chicago, in the county of Cook and State 5 of Illinois, having invented certain new and useful Improvements in Toys, do hereby declare that the following is a full, clear, and exact description of the same, reference being had to the accompanying drawing. 10 My invention relates to toys, and consists in the matters hereinafter described and then pointed out in the appended claims.

In the drawings, the figure is a side elevation of a device embodying the features of 15 my invention.

The reference numeral 1 indicates a standard upon which the device is mounted and which is adapted to be held in the hand of the user or mounted to freely turn in a socket 20 2. The standard carries a rigid open frame of rectangular form, the upper and lower members 3 and 4 of which are fixed to the standard as shown, and the side members 5 and 6 of which are connected at their tops 25 and bottoms to the other members. A rearwardly projecting vane 7 is rigidly mounted on the upper portion of the rear side 6 of the frame, and a cross-shaft 8 is revolvably mounted in the sides 5 and 6, being held 30 against longitudinal displacement by opposite end collars 9 and passing freely through the standard 1; this shaft projects forwardly beyond the front side 5 where it carries a fan-propeller 10, which is rigidly 35 mounted on its end by a set-screw 11 passing through a hub 12 on the fan. A friction disk or wheel 13 is secured on the shaft 8 by a set-screw 14 passing through its hub 15, being preferably located adjacent the 40 inner side of the front member 5 of the frame and adapted to rotate when the fan turns the cross-shaft. A rotating platform 16 is fixed to a sleeve 17 which is mounted to freely turn on the upper portion of the 45 standard and rests upon a collar 18 fixed on the standard, the collar in the present case extending below the cross-shaft 8 and

being oppositely perforated to allow the shaft to freely rotate. The platform 16 is so placed that its under face is in frictional 50 engagement with the disk 13, whereby the cross-shaft 8 is revolved by the fan and the platform is rotated about the standard. The disk 13 is preferably provided with a rubber rim or tire 19 to more positively engage 55 and drive the platform, as well as to eliminate all noise between these parts. The platform may carry various objects or figures, such as the miniature ships 20 and sailors 21, and as the platform is located in the 60 frame all these parts are protected by the frame.

When the toy, carried either in the hand of the user or in the socket 2, is exposed to the wind the propeller-fan is turned thereby 65 and the platform with its figures or objects is rapidly rotated, and the same effect is produced by the user carrying the toy through the air; when the toy is in the socket the vane 7 acts to keep the fan in the line 70 of the wind.

It is obvious that the device may be used as a weather vane, and may be made of any suitable material in accordance with the character of its use.

I claim:

A device of the class described comprising an open rectangular frame, a standard centrally secured to the upper and lower members of the frame and extending below 80 the latter, a collar fixed on the standard, a sleeve revolvably mounted on the standard above the collar, a platform located in the frame and carried by the collar, a cross-shaft revolvably mounted in the sides of the frame 85 below the platform and having one of its ends extending beyond the frame, a friction-disk fixed on the cross-shaft in driving engagement with the platform, and a fan-propeller fixed on the extended end of the 90 cross-shaft.

In testimony whereof I affix my signature.

HENRY JENSEN.
